CHARLES A. SINGER, OF ST. LOUIS, MISSOURI, ASSIGNOR TO SINGER AUTO TRAFFIC SIGNAL COMPANY, OF ST. LOUIS, MISSOURI, A CORPORATION OF DELAWARE.

TRAFFIC-DIRECTING SIGNALING DEVICE.

1,239,832.

Specification of Letters Patent. Patented Sept. 11, 1917.

Application filed May 12, 1915. Serial No. 27,591.

To all whom it may concern:

Be it known that I, CHARLES A. SINGER, a citizen of the United States, residing at St. Louis, Missouri, have invented a certain new and useful Improvement in Traffic-Directing Signaling Devices, of which the following is a full, clear, and exact description, such as will enable others skilled in the art to which it appertains to make and use the same.

This invention relates to traffic directing signals for vehicles.

The main object of my invention is to provide an efficient traffic directing signaling device for automobiles and similar vehicles by which the operator in charge of the vehicle can indicate a proposed change in the direction or speed of travel of the vehicle, as, for example, that it will either turn to the right, or the left, or turn completely around or stop or slow down.

Another object is to provide a traffic directing signaling device for vehicles comprising indicators arranged in such a manner that they can be seen from the front and from the rear of the vehicle when they are in operative position and which are illuminated at night when in an operative position.

And still another object is to provide a traffic signaling device for vehicles that comprises a plurality of indicators and a selecting means under control of the operator in charge of the vehicle on which the device is used for operating a selected indicator or rendering it operative, the complete device preferably consisting of two sets of indicators arranged so that they can be seen from the front and from the rear of the vehicle when operative and combined with a selecting means under control of the operator in such a manner that the indicators of both sets, which are of the same character, will operate simultaneously. Other objects and desirable features of my invention will be hereinafter pointed out.

In the embodiment of my invention herein illustrated the complete device comprises two sets of similar indicators arranged so that they can be seen from the front and from the rear of the vehicle on which the device is used, and means under control of the operator in charge of the vehicle for operating the indicators at the front and

at the rear of the vehicle that are of similar character, or causing said indicators to become operative prior to a change in the direction of travel of the vehicle or prior to a change in the method of operating the vehicle. The indicators of each set are preferably normally arranged in an inoperative position or in such a manner that they are hidden from view. The mechanism for operating said indicators consists of a plurality of controlling devices, any one of which can be actuated by the operator so as to cause the pair of indicators with which said device cooperates to become operative. Means is preferably employed for illuminating the indicators at night, which means may consist of electric lights that either burn continually at night or which light automatically whenever any one pair of indicators is rendered operative.

Figure 1 of the drawings is a diagrammatic view, illustrating the electric circuits of my improved traffic directing signaling device.

Fig. 2 is a vertical sectional view of one of the indicator housings, showing the indicators arranged inside of same.

Fig. 3 is an elevational view of said indicator housing, with the front cover removed and the indicators in the housing broken away so as to more clearly illustrate the construction of the controlling devices.

Fig. 4 is a detail view of one of the magnets that forms part of the mechanism for operating one set of indicators.

Fig. 5 is a longitudinal sectional view of one of the manual controlling devices used to govern the indicators.

Fig. 6 is an elevational view of the insulating plate that carries the contacts which cooperate with the contacts on the controlling devices.

Fig. 7 is a top plan view of the electrically operated mechanism that is employed for actuating one group of indicators; and

Fig. 8 is an elevational view of the indicator housing in which the electrically-operated indicators are arranged, the front wall or cover plate of said housing being removed so as to more clearly illustrate the construction of the indicator-operating mechanism.

My complete traffic directing signaling device comprises two groups or sets of indi-

cators, one of said groups being arranged in a housing A, shown in Figs. 2 and 3, that is arranged so that the indicators of same can be seen from the front of the vehicle 5 when they are operative and the other group being arranged in a housing A' that is so arranged that the indicators of same can be seen from the rear of the vehicle when they are operative. It is immaterial, so far as 10 my invention is concerned, how these housings A and A' are arranged on the vehicle, so long as they are located in such a position that the indicators in same can be seen readily from the front and from the rear of the 15 vehicle. As both of said housings are of substantially the same construction, I will only describe the housing A at the front of the vehicle, which is illustrated in Figs. 2 and 3. Said housing A preferably consists 20 of a substantially box-shaped metal casing whose cover plate or front wall 1 is removable and provided with a sight opening 1*, shown in Fig. 2, over which a piece of glass or a transparent member 2 extends. A plurality of indicators B are arranged vertically in the housing A in such a manner that they can be moved vertically into and out of alinement with the sight opening in the front wall of the casing, the casing shown in 25 Figs. 2 and 3 being provided with five indicators B that have indicia thereon for indicating a proposed change in the direction or speed of the vehicle. For example, one of the indicators can be provided with the 30 word "Right", to indicate a turn of the vehicle to the right; another provided with the word "Left"; another with the word "Turn"; another, with the word "Slow" and the other, or remaining indicator, with 35 the word "Stop". Instead of being provided with words for designating a change in the direction or speed of the vehicle, the indicators B can be provided with other indicia. The particular details of construction 40 of the indicators B are, of course, immaterial, but I prefer to form each indicator from a rectangularly-shaped frame 3, as shown in Fig. 3, that surrounds a web 4 having perforations or cut-out portions that 45 constitute the words previously mentioned, so as to enable the indicators to be illuminated at night, as hereinafter described. If desired, said web 4 can be provided with a strip of translucent material that extends 50 over the cut-out portions in same so as to diffuse the light employed to illuminate the indicator. The indicators B are normally arranged in the lower portion of the housing A, one behind the other, as shown in Fig. 2, being retained in this position by means of vertically-disposed guideways or 55 flanges 5 on the end walls of the casing A. Various means may be employed for moving the indicators B into and out of operative position with relation to the sight open- 60

ing 1* in the front wall of the housing A, but I prefer to operate said indicators manually by means of a plurality of movable controlling devices C which are operatively connected with the indicators B by cords or 70 cables 6, as shown in Figs. 2 and 3. Five controlling devices are slidably mounted on the rear wall of the housing A, and each of said devices is secured to a pair of flexible members or cables 6 that lead from the opposite ends of the particular indicator B with which said device co-operates, upwardly through guides 7 on the end walls of the housing A, then transversely of said housing to a guide 8 arranged on the top 75 wall of said housing in vertical alinement with the controlling device C. Said controlling devices C are preferably slidably mounted in vertically-disposed slots 9 in the rear wall of the housing A, each of said devices having a non-circular shank 10, shown in Fig. 5, that fits snugly in its corresponding slot 9, a friction device 11, preferably a resilient washer, arranged in such a manner that it will bear upon the inner side of the 80 rear wall of the housing A and a sleeve 12 that engages the connecting cable 6 of the indicator. In the construction herein shown a single or continuous cable is provided for each indicator, which cable runs from one 85 end of the indicator to the sleeve 12 and then around said sleeve to the opposite end of the indicator. This, of course, is a detail that could be changed in various ways. In view of the fact that the controlling devices C govern the operation of the electrically-operated mechanism employed to actuate the indicators B at the rear of the machine which are arranged in the housing A', I have provided each of the controlling devices C with a spring contact 13 that is 90 adapted to engage co-operating contacts when said device C is operative, said spring contact 13 and the sleeve 12 and washer 11 being connected to the controlling device 95 by a screw 14, as shown in Fig. 5. 100

One or more electric lamp bulbs 15 are arranged inside of the housing A, so as to illuminate the indicator in said housing that is in an operative condition, or, in other 105 words, which is arranged in alinement with the sight opening in the front wall of said housing, said bulbs being mounted in sockets 16 carried by an insulating strip 17 which is supported by brackets 18. This insulating 110 strip 17 is provided with five pairs of stationary contacts 19, shown in Fig. 6, which are so arranged that they will co-operate with the spring contacts 13 on the controlling devices C, the contact of each controlling device engaging one pair of the contacts 19 115 when said controlling device is moved into its operative position as shown in Fig. 2. 120

The housing A' at the rear of the machine is provided with five electro-magnets 20 for 125 130

operating the indicators B in said housing, each of said magnets being so arranged that it will depress or actuate a lever 21 when the magnet is energized, said lever being preferably connected to the armature of the magnet. The arms or levers 21 are operatively connected to the indicators B by means of cables 6 in practically the same manner that the controlling devices C are connected to the indicators in the housing A at the front of the machine. Normally, the indicators B in the housing A' are arranged in the lower portion of said housing in such a position that they are hidden from view, but whenever one of the magnets 20 is energized, the particular indicator that coöperates with said magnet will be raised upwardly into operative position as shown in Fig. 8. The housing A' is also equipped with one or more electric lamp bulbs 15*, so as to illuminate the indicators in said housing at night.

The electric lights in the housings A and A' and the electrically-operated mechanism in the housing A' are energized by a battery or other suitable source of electrical energy, as shown in Fig. 1, the circuits in which the various lighting units and operating magnets 20 are arranged being so designed that the magnets 20 will be rendered operative automatically when the controlling devices C are rendered operative. In order that the lighting units may be cut out of service during the day I have arranged a switch 22 in the energizing circuit, as shown in Fig. 1. When said switch 22 is closed the lighting units in both of the housings A and A' will operate automatically whenever the controlling devices C are rendered operative, but when said switch 22 is open the depression of one of the controlling devices C will cause only its corresponding magnet 20 to be energized. In other words, the spring contact 13 of each of the controlling devices C coöperates with two contacts 19, one of which governs one of the electromagnets 20 and the other governs the circuit in which the lighting units are arranged. If the switch 22 is closed when one of the controlling devices C is depressed so as to cause its spring contacts 13 to engage one of the pairs of contacts 19, the source of light in both of the housings A and A' will operate and one of the magnets 20 will operate, but if said switch 22 is open, only the magnet will be energized.

When the operator in charge of the vehicle desires to indicate a proposed change either in the direction or speed of the vehicle, as, for example, that the vehicle will turn to the right, he depresses the controlling device C that coöperates with the indicator B provided with the word "Right," thereby manually raising the indicator thus marked in the housing A and causing the corresponding indicator in the housing A'

to be moved upwardly by the electrically-operated mechanism in the housing A'. If the switch 22 is closed, the lighting units in said housings will light up, and thus illuminate the two indicators that have been rendered operative. After the change in the direction of travel has been effected the operator restores the controlling device C to its former position, thereby rendering both of the indicators inoperative and causing the lights to be extinguished.

While I prefer to use two groups or sets of indicators arranged so that they can be seen from the front and from the rear of the vehicle, I do not wish it to be understood that my broad idea is limited to a traffic directing signaling device that comprises two groups of indicators, as one feature of my invention consists in a traffic directing signaling device comprising a housing or casing containing a plurality of indicators of different character that are normally inoperative and a selective controlling means for enabling the operator in charge of the vehicle to operate or render operative a selected indicator. Furthermore, while I prefer to actuate one group of indicators manually and the other group of indicators by an electrically-operated mechanism, it will, of course, be obvious that various other means could be employed for actuating the indicators and for causing the indicators of a similar character to operate simultaneously.

A traffic directing signaling device of the construction herein described forms an efficient means for indicating a proposed change in the direction or speed of travel of a vehicle; it comprises indicators which can be readily seen during the day, as well as at night and it is of such a character that it can be applied easily to automobiles and horse-drawn vehicles.

Having thus described my invention, what I claim, and desire to secure by Letters Patent, is:

1. A traffic signal for vehicles, comprising two groups of indicators arranged at the front and at the rear of the vehicle and each composed of a plurality of indicators of different character, a manually-operated selective means for actuating the indicators of one group, and an electrically-operated mechanism controlled by said manually-operated selective means for actuating the indicators of the other group.

2. A traffic signal for vehicles, comprising two groups of indicators arranged to be seen from the front and from the rear of the vehicle and each composed of a plurality of indicators of different character, a manually-operated selective means for moving the indicators of one group into operative position, and an electrically-operated mechanism for actuating the indicators of the other group, said mechanism being so con-

structed that the indicators controlled by same will operate in a synchronism with the indicators controlled by said manually-operated governing means whenever said means is operated.

3. A traffic signaling device for vehicles, comprising two groups of indicators, each of which is composed of a plurality of indicators of different character, a plurality 10 of manually-operated controlling devices, means for transmitting movement from said controlling devices to the indicators of one group, an electrically-operated mechanism for actuating the indicators of the other group, and means on said controlling devices for closing the circuit that energizes 15 said electrically-operated mechanism.

4. A traffic signaling device for vehicles, comprising two groups of indicators, each 20 of which is composed of a plurality of indicators of different character, a plurality of manually-operated controlling devices, means for transmitting movement from said controlling devices to the indicators of one 25 group, an electrically-operated mechanism for actuating the indicators of the other group, and contacts on said controlling devices that are adapted to engage contacts that form part of the circuit in which said 30 electrically-operated mechanism is arranged when said controlling devices are in an operative position.

5. A traffic signaling device for vehicles, comprising two groups of indicators, each 35 of which is composed of a plurality of indicators of different character, a plurality of manually-operated controlling devices, means for transmitting movement from said controlling devices to the indicators of one 40 group, electrically-operated mechanism for actuating the indicators of the other group, contacts on said controlling devices that are adapted to engage contacts that form part of the circuit in which said electrically-operated 45 mechanism is arranged when said controlling devices are in an operative position, and illuminating devices for said indicators that operate automatically whenever

one or the other of said controlling devices is rendered operative. 50

6. A traffic signaling device for vehicles, comprising two housings arranged at the front and rear of the vehicle, groups of indicators in said housings that are normally in an inoperative condition, a bank of manually-operated controlling devices, means for transmitting movement from said controlling devices to the indicators of one group, electro-magnets for operating the indicators of the other group, lighting devices for illuminating the indicators in said housings, 60 contacts on said controlling devices, each of which cooperates with a pair of contacts, one of which is arranged in the electro-magnet circuit and the other in the lighting circuit, 65 and a switch for enabling said lighting devices to be cut out of service.

7. In a signaling apparatus for vehicles, the combination of a master signal device comprising a manually-operated signal, a 70 secondary signal device comprising a movable signal, an electro-magnet for the operation of the said movable signal, and an electric circuit, including a portion of said manually-operated signal and the electro-magnet 75 that operates the movable signal of the secondary device.

8. In a signaling apparatus for vehicles, the combination of a master signal device comprising a manipulative signal, a secondary signal device comprising a movable signal, an electro-magnet for the operation of the signal of the secondary device, an electric circuit, including a portion of said manipulative signal and the electro-magnet of 80 the secondary device, an electric illuminant associated with each signal device, and means for controlling said illuminant.

In testimony whereof I hereunto affix my signature in the presence of two witnesses, 85 this seventh day of May 1915.

CHARLES A. SINGER.
